UNITED STATES PATENT OFFICE.

GEORGE C. LUNT, OF GREENFIELD, MASSACHUSETTS, ASSIGNOR TO
ROGERS LUNT & BOWLEN COMPANY, OF GREENFIELD, MASSA-
CHUSETTS, A CORPORATION OF MASSACHUSETTS.

DESIGN FOR A HANDLE FOR SPOONS, FORKS, OR SIMILAR ARTICLES.

No. 37,699.

Specification for Design.

Patented Nov. 28, 1905.

Application filed October 28, 1905. Serial No. 284,115. Term of patent 14 years.

To all whom it may concern:

Be it known that I, GEORGE C. LUNT, a citizen of the United States, residing at Greenfield, in the county of Franklin and State of Massachusetts, have invented a new, original, and ornamental Design for a Handle for Spoons, Forks, or Similar Articles, of which the following is a specification, reference being had to the accompanying drawing, forming part thereof.

The figure is a plan or front view of a handle for spoons, forks, or similar articles, showing my new design.

I claim—

The ornamental design for a handle for a spoon, fork or similar article, as shown.

GEORGE C. LUNT.
